UNITED STATES PATENT OFFICE.

WILLIAM CLAYTON CORYELL, OF YOUNGSTOWN, OHIO, ASSIGNOR TO THE GENERAL FIREPROOFING COMPANY, OF YOUNGSTOWN, OHIO, A CORPORATION OF OHIO.

METHOD OF STONE-SURFACING FIBROUS MATERIALS.

1,354,025.

Specification of Letters Patent. Patented Sept. 28, 1920.

Application filed July 9, 1919. Serial No. 309,631.

To all whom it may concern:

Be it known that I, WILLIAM CLAYTON CORYELL, citizen of the United States, residing at Youngstown, in the county of 5 Mahoning and State of Ohio, have invented certain new and useful Improvements in Methods of Stone-Surfacing Fibrous Materials, of which the following is a specification.

10 This invention relates to the general subject of coating processes and more particularly to the surface coating of fibrous materials having an oiled or waterproof surface.

Certain materials are rendered more available for industrial purposes by being subjected to treatment to render the same waterproof and fire-resistant, and that particularly applies to building materials or building fabrics which are employed as substitutes for wood and metal lathing and for other building purposes. It is quite important in the production of a building fabric for such purposes that the fibrous sheet forming the body part of the fabric shall 20 be treated with a suitable water repelling substance as oil, tar or equivalent medium, and it is likewise desirable and important to supplement this treatment by providing the waterproofed body with a coating or envelop of a non-combustible artificial stone compound so as to render the completed product quite fire-resistant. This will also apply to any fibrous material or fibrous object in which it is desired to supplement the 25 waterproofing treatment by a fireproofing treatment, and the present invention has chiefly in view a novel method of combining waterproofing and fireproofing treatment of a fibrous material in such a manner as to obtain an effective and homogenous bonding 30 between the oiled or waterproof surface, and the stone-surfacing of non-combustible material as for instance an artificial stone compound.

35 The invention is necessarily susceptible of modification within the limits of the appended claims but may be well exemplified by the graphic illustrations of the drawings, wherein:—

40 Figure 1 is a greatly magnified view of a section of fibrous material such as paper, rope, felt or other equivalent, the fibers of which have been given a bath of oil, asphaltum or other waterproofing substance.

45 Fig. 2 is a view of the same section of

fibrous material showing the important intermediary step of the process wherein the interstices or spaces between the fibers have been filled in with non-oily particles of a non-combustible material. 60

Fig. 3 is a view of the same material showing the general step of the process wherein the artificial stone compound has been amalgamated or consolidated with a non-oily filling material. 65

In carrying out the method of the present invention it will be understood, as above indicated, that the same is not limited in its application to any particular fibrous materials which are to be water-proofed and fire-proofed, nor is it confined to the use of any particular substances or compounds for primarily water-proofing the fibers, then filling in the pores or interstices with a non-oily substance, and finally producing a homogeneous artificial stone coating or surface. Accordingly, it will be understood that the distinctive and important feature of the invention resides in the method which is employed, by the use of suitable substances, for the purpose of obtaining an effective bond between the waterproofed surface and the stone-surfacing of non-combustible material. This may be well explained by reference to the graphic illustrations of the drawings. In these illustrations the fibrous material designated as F is shown highly magnified or enlarged to expose the pores or interstices between the individual fibers, and Fig. 1 will represent the fibrous material waterproofed by treatment with a suitable water-repelling substance, such as oil, tar or an equivalent oily medium. When a fibrous material is thus filled and covered with an oily waterproofing substance the latter provides an unctuous or greasy surface on and throughout the fibrous body which acts to prevent the adhesion of water or watery substances and therefore is repellent thereto. This makes it difficult and almost impossible for the fibrous material thus waterproofed to receive or contain any continuous coat and artificial stone compound which is usually in liquid form with a considerable percentage of water therein. 90 95

Therefore it is proposed by the present invention to introduce in the process of stone surfacing a waterproofed or oiled material an intermediary step which provides for preparing the material in such a way that an 100 105 110

artificial stone compound may be thoroughly and effectively bonded into and on the material. The treatment of the waterproofed or oiled fibrous material which renders this 5 desirable result possible consists in filling, as completely as possible, the pores or interstices between the fibers with a non-oily substance such as very fine sand or dust. This 10 non-oily substance may be incorporated in the waterproofed or oiled fibrous material in any suitable manner as by rubbing, pressing or otherwise working the same into and throughout the fabric so that the pores or interstices thereof will be filled thereby as 15 shown by the graphic enlargement of Fig. 2 of the drawings, the said non-oily filling material being indicated in said figure by the reference numeral 1.

The non-oily filler when thus intimately 20 incorporated with and throughout the fibrous material becomes tightly interlocked therewith and presents a body to which an artificial stone compound can be effectually bonded. In fact a filler material of the character 25 referred to readily induces stone-forming compounds when liquid to wet the surface, and such compound while solidifying will in effect incorporate, by adhesion or otherwise, the non-oily particles of non-combustible material into its own body, thereby 30 adhering to or becoming interlocked with the fibers of the material in a manner quite similar to what would have occurred if its own substance had penetrated into the pores 35 of the oiled surface before solidification.

It will, therefore, be seen that when a liquid artificial stone compound, of any desirable composition, as for instance silicate of soda, infusorial earth and oxid of zinc, 40 is applied to a waterproofed or oiled fibrous body having a non-oily filler substance incorporated therewith, the stone compound will become securely bonded or consolidated with the filler substance in such a manner 45 as to constitute in effect a homogenous stone-like body throughout the fibrous material and forming the surface therewith.

Should it be desirable, in carrying forward the process to facilitate and expedite 50 the drying of the stone compound the latter when in the liquid state may be sprinkled with a non-combustible dust or granular substance, as sand. This dusting operation, furthermore, has the effect of thickening the 55 stone coating and giving the finished surface a granular or sand stone finish or texture and also tending to close any crack or fissures that might develop in the drying of the stone compound.

60 From the foregoing it is thought that the particular features of the invention have

been fully pointed out, though it will be understood that any minor variations therein may be resorted to without departing from the spirit or sacrificing any of the advantages of the invention.

I claim:

1. The herein described method of preparing fibrous sheet materials which consists in preliminarily filling the pores or interstices opening at the exposed faces thereof with a powdered filling substance, and subsequently enveloping the said material and filling substance with a plastic artificial 75 stone compound.

2. The herein described method of preparing fibrous material impregnated with an oily substance which consists in preliminarily filling the pores or interstices thereof 80 with an non-oily dry dust, and subsequently saturating the said material and dry dust filler with a plastic artificial stone compound.

3. The herein described method of preparing relatively porous water repelling sheet which consists in preliminarily subjecting the said relatively porous sheet to a bath of non-combustible dust, and subsequently applying in liquid form a layer of 90 non-combustible substance.

4. The herein described method of preparing relatively porous water repelling sheet which consists in preliminarily subjecting the said relatively porous sheet to 95 a bath of non-combustible dust, then applying in liquid form a layer of non-combustible substance, and subsequently drying the latter by an application of a coat of non-combustible dust.

5. A method of water-proofing and fire-proofing relatively porous sheet materials having an oily base which consists in first applying to said base a water proofing substance in form of a dust to fill the voids of 105 the relatively porous base, and subsequently applying an artificial stone compound in liquid form to the dust impregnated base.

6. A method of water-proofing and fire-proofing relatively porous sheet materials 110 having an oily combustible base, which consists in first rubbing a dust of water-proofing substance into the voids of the relatively porous base, and subsequently applying a coating of liquid artificial stone compound to 115 the dust impregnated base to envelop the same.

In testimony whereof I hereunto affix my signature in the presence of two witnesses.

WILLIAM CLAYTON CORYELL.
